UNITED STATES PATENT OFFICE

WILLIAM B. SNOW, OF CHICAGO, ILLINOIS.

IMPROVEMENT IN SLEEPING-CAR BERTHS.

Specification forming part of Letters Patent No. 103,097, dated May 17, 1870.

To all whom it may concern:

Be it known that I, WILLIAM B. SNOW, of Chicago, in the county of Cook and State of Illinois, have invented a new and Improved Sleeping-Car Berth; and I do declare that the following is a full and accurate description thereof, reference being had to the accompanying drawings, and to the letters of reference marked thereon, and being a part of this specification, in which my device is shown in perspective.

The nature of this invention relates to an improved method of hanging the upper berth of sleeping-cars; and consists in a coiled spring within a drum, around which a cord passes, one end of which is secured near the front of the berth, which is hinged, in the usual manner, to the side of the car, the whole arranged so that the spring acts as a counter-balance to the berth, as more fully hereinafter described.

In the accompanying drawings, A represents a section of one side of a sleeping-car, to which is hinged, in the usual manner, the berth B, so that when closed its lower side forms a part of the ceiling of the car. Cords C are fastened at one end at or near the front of the berth, and at each end thereof, and thence are led over and around the drums D, which rotate within suitable yokes E, which are secured to the car, as shown in the drawings. Within these drums, and around the axis thereof, are coiled suitable springs, secured to the drums in such a manner that

when the berth is let down to a position at right angles with the vertical walls of the car said springs will be tightly coiled around the axis of the drum, and when the berth is put up the coil of the spring will be loosened and exert less power. F are jointed rods, one end secured to the car and the opposite end to the front of the berth, as shown, which sustain the berth when in a horizontal position.

I do not wish to confine myself exactly to the device as shown; for instance, the drums may be conical in form, or a single spring may be used, secured to the ceiling of the car over the center of the berth, with cords leading therefrom to and over pulleys placed where the drums are shown, and thence to the front of the berth.

This application is designed to be an improvement upon the patent granted to me on the 25th day of February, 1868.

What I claim as my invention, and desire to secure by Letters Patent, is—

The combination of the drum D, provided with a coiled spring in its interior, and the cord C, one end of which is wound around said drum, and the other end is secured to the front of the berth, when constructed as described, and arranged to operate as and for the purpose set forth.

W. B. SNOW.
